UNITED STATES PATENT OFFICE.

MARTIN BOHLIG, OF ST. PAUL, MINNESOTA, ASSIGNOR OF ONE-HALF TO PAULINE BOHLIG WARNER, OF ST. PAUL, MINNESOTA.

VENDING MACHINE.

Application filed April 18, 1925, Serial No. 24,132. Renewed June 30, 1928.

My invention relates to improvements in vending machines of the coin controlled type, the same being designed particularly, though not exclusively, for dispensing match filled boxes.

An object of the invention is to provide a simple, durable and relatively inexpensive apparatus of the instant nature, wherein dual dispensing devices are operated by a single actuator and caused alternately to vend match boxes or like packets.

Another object of the invention is to provide a machine of the present kind, wherein the vending mechanism is normally locked against actuation, but freed to function upon the application of a coin thereto.

A further object is to supply a coin controlled vending machine including an actuating lever arranged to guard the coin slot in all except the extreme positions of the actuating lever, wherein the slot is cleared to receive a coin preparatory to the initiation of movement of said lever.

With the foregoing and other objects in view, which will appear in the following description, the invention resides in the novel combination and arrangement of parts and in the details of construction hereinafter described and claimed.

In the drawings, Fig. 1 is a perspective view of a vending machine embodying my invention; Fig. 2 is a fragmentary elevational view of the lower forward portion of the machine, parts of the structure being broken away to disclose various details that otherwise would be concealed; Fig. 3 is a detail sectional view of the machine, the same being taken as on the line 3—3 of Fig. 2; Fig. 4 is a horizontal sectional view taken as on the line 4—4 of Fig. 3; Fig. 5 is a similar view taken as on the line 5—5 of said Fig. 3; Fig. 6 is a detail sectional view taken on the line 6—6 of Fig. 3; Fig. 7 is a like view taken on the line 7—7 of Fig. 4 and Fig. 8 is a detail perspective view of the dual coin embracing yoke.

Referring to the drawings, it will be observed that my improvement consists of a box-like base A and a tower-like structure B. The base A includes a bottom frame-plate 10 and an upper frame-plate 11. A plate 12 secured at its upper edge to the upper frame-plate 11 and at its lower edge to the bottom frame-plate 10 constitutes the front

of the base A. Side plates 13, 14, attached to the frame-plates 10, 11, are formed with riser portions 13', 14', at the rear thereof, said riser portions being integral with a deck-plate 15, which has a flange 15' turned down from the rearward edge thereof and secured at its lower margin to the rear edge of the upper frame-plate 11. Hinged on said flange 15' is a pendant door 16 for the back of the base A, said door being equipped with a lock 17 co-operating with a catch 18 on the bottom frame-plate 10. The tower-like structure B includes a sheet metal body b stamped to form a pair of spaced magazines or chutes 19 U-shaped in transverse section (Fig. 5). The outer sides of the body b are extended to form legs 20, which are received within recesses in the upper and bottom frame-plates 10, 11 and secured to said plates. A door 21 hinged at its lower edge to the deck-plate 15 normally closes the backs of the magazines 19 and a lock 22 on said door co-operates with a catch 23 on a cover 24 fitted on the body b and capping said magazines 19. The front magazine panels b' of the body b have sight openings 25 stamped therein, the lower edges 80 of said panels lying in the horizontal plane of the deck-plate 15 of the base A.

At the bottom of each magazine 19 is a combination vending device C each forming a box support and vending tray. 85 These vending devices are identical, each being formed from a strip of sheet metal bent to provide a base-plate 26, an elevated rest 27 at the rear of the device and an upright guard flange 28 at the front of the device. Each vending device C has a pair of studs 29 depending from the base-plate 26 thereof and riding in a guide-slot 30 in the upper frame-plate 11. These studs 29 guide the vending devices C as they slide back and forth on the frame-plate 11 under the deck-plate 15 of the base A and through the bottoms of the magazines 19. In the retracted position of a vending device C (Figs. 3 and 4), the box rest 27 is disposed beneath the deck-plate 15, the tray portion between said rest 27 and the front guard flange 28 being then sheathed within the magazine to receive the lowermost box of the stack therein. The forward projection of said device from said retracted position results in shifting the box rest 27 under said stack of boxes and in unsheathing said tray portion of said device to

permit of the removal of the contained box therefrom. A lever 31 is pivoted between its ends, as at 32, to the upper frame-plate 11, the forward end of said lever overreaching the front of the base A and providing a convenient handle 31^a for swinging the lever, the rear end of said lever having opposed ears 31^b (Fig. 4) formed thereon. Opposed cam-links 33 respectively pivoted to the ears 31^b on the lever 31 join said lever with two vending devices C. The connection between each link 33 and its respective vending device is made through an upstanding pin 34 in the link, said pin being inserted in a slot 35 traversing the base-plate 26 of the vending device. Each cam-link 33 has an angular cam-slot 33^a formed therein and into which projects an upstanding fulcrum pin 35 which is anchored in the upper frame-plate 11. In the extreme positions of the lever 31 (solid and dotted lines, Fig. 4), one vending device C is retracted and the other projected, while, in the intermediate position of said lever, both devices are to be found in retracted position. In other words, the first half stroke of the lever 31 in one direction retracts the previously projected vending device C, while the last half stroke of said lever in the same direction projects in the other vending device C.

A coin controlled latching device D is associated with the lever 31 to prevent the vending of boxes from the machine except upon the application thereto of a coin. Depending beneath the upper frame-plate 11 is a cage consisting of forward and rear walls 36, 37 spaced slightly apart to form a coin slide transversely of the lever 31. A dual coin embracing yoke d (Fig. 5) is provided, the same including a block 38 slidable in a slot 39 in the upper frame-plate 11, said block 38 being formed with a pair of outer depending branches or fingers 38^a, and an intermediate branch or finger 38^b. A pin 38^c rising from the block 38 fits in a slot 40 in the lever 31 and serves to connect said block 40 with said lever 31. The fingers 38^a, 38^b depending from said block 38 reach downward into the way or slide between the walls 36, 37 of the coin cage. This coin receiving way is closed at the bottom thereof medially of the cage by means of a bottom piece 36^a, the ends of said cage being open at the bottom to allow coins to drop from either extremity thereof into the box-like base A. Reaching into the coin slide between the walls 36, 37 and through an opening 37^a in the rear wall 37 of the cage are a plurality of yielding spring pressed tumblers 41. The tumblers 41 hinged on a common hinge-pin 42 are disposed along the wall 37 at the medial portion thereof and over the bottom piece 36^a on the wall 36. The yoke-fingers 38^a, 38^b are spaced apart so that one terminal finger 38^a and the intermediate finger 38^b will embrace the extreme tumblers 41 in either of the extreme positions of the lever 31. A cover-plate 43 placed over the block receiving slot 39 in the upper frame-plate 11 has a slot 44 therein in which the pin 38^c on the block 38 may play and is further provided with a slot 45 for coins. Thus formed with said slot 45, the cover-plate 43 constitutes a coin guide through which coins may be inserted into the spaces between the branches of the yoke d and the walls 36, 37. This coin guide, however, is unobstructed by the lever 31 only when said lever is in one of its extreme positions (Fig. 4). In either of such positions of the lever 31, a coin inserted into the coin slot 45 passes between the medial yoke branch 38^b and one of the terminal branches 38^a. A coin thus disposed engages and swings all of the tumblers 41 rearward, and in so retracting said tumblers causes the way between the walls 36, 37 to be cleared for the movement therewith of the yoke-fingers 38^a, 38^b. As the lever 31 is swung to deliver a box through one of the vending devices C, the tumblers 41 progressively enter the coin slide behind the intermediate yoke-finger 38^b and thereby lock said lever against reversal at various steps in either operating throw thereof. In being pushed past the tumblers 41 by the yoke-finger 38^b, a coin holds said tumblers retracted until they are progressively overreached by said finger, the coin being finally thrust beyond the bottom piece 36^a, after traversal of the last tumbler 41 by said coin, whereupon the coin drops upon the bottom plate 10.

In use, the person attending the machine keeps the magazines 19 filled with stacked boxes, access to said magazines being had through the lock guarded door 21. Access to the box-like base A to permit of collection of deposited coins is had through the lock guarded door 16. A customer finding the lever 31 in one extreme position or the other, inserts a coin in the slot 45 and shifts said lever into opposed extreme position. On the first half throw of the lever 31 the projected device C is retracted, the tray portion thereof being sheathed in its respective magazine 19 to receive the lower box of the stack therein. On the final half throw of said lever 31, the previously sheathed device C is projected from its respective magazine 19, the same presenting the contained box to the customer. The flange 28 of the sheathed vending device C guards its respective magazine and the tumblers 41, locking the yoke-fingers 38^a, 38^b against movement between the cage walls 36, 37, prevents actuation of the lever 31 in the absence of a tumbler retracting coin.

While I have stated that my improved machine is designed particularly for vending match filled boxes and while I have used the expression "boxes" throughout the specification, it will be understood that I do not limit myself to a vending machine for boxes alone, since it is obvious that suitably sized packages,

packets, cakes, and the like may be dispensed from my machine in a most satisfactory manner.

Changes in the specific form of my invention, as herein disclosed, may be made within the scope of what is claimed without departing from the spirit of my invention.

Having described my invention, what I claim as new and desire to protect by Letters 10 Patent is:

1. In a machine of the class described, a base, a pair of box receiving magazines rising from said base, combined vending tray and stack supporting devices, one for each magazine, each device being slidable forward and back through its respective magazine at the bottom thereof, a lever pivoted between its ends to said base, cam-links, one for each of said devices, each link joining its respective 15 device with said lever and having a sliding fulcrumed connection with said base, said links serving, upon one throw of said lever to retract one device from vending position and then project the other device into such 20 position.

2. In a machine of the class described, an upright magazine adapted to contain a stack of boxes, a sliding device movable backward and forward through the bottom of said magazine and comprising a combined vending tray and stack support, an actuating lever, and a cam-link, said cam-link slidably fulcrumed and joining said lever with said device, whereby upon a throw of said lever, in 30 one direction, said device is projected into vending position and upon the reverse throw of said lever said device is retracted into box receiving position.

3. In a machine of the class described, a 40 pair of upright magazines, each adapted to receive a stack of boxes and being formed at the bottom thereof with an opening for the removal therethrough of the lowermost box of the stack, a vending device for each magazine, each device being movable forward and back through its respective magazine to deliver boxes one after the other through the delivery opening therein, each device being formed with a guard flange for closing the 45 delivery opening of its respective magazine in the retracted position of the device, a lever pivoted to swing between the two extreme 50 positions, a pair of links pivoted to said lever, one link having a slidable pivotal connection

with one of said devices and the other link 55 having a similar connection with the other of said devices, each link having an angularly formed slot therein, a fulcrum for each link in slidable co-operation with the slot of its respective link, the relation of said lever, links 60 and vending devices being such that in one extreme position of the lever one device occupies retracted position with its flange closing the delivery opening of its respective magazine while the other device rests in projected delivery position, said links serving, upon a throw of said lever from one extreme 65 position to the other, to retract the projected vending device and thereafter project the retracted device.

4. In a machine of the class described, a pair of upright magazines, each adapted to receive a stack of boxes, a vending device for each magazine, each device being movable forward and back through its respective magazine severally to deliver boxes therefrom, a pivoted lever, a pair of links pivoted to said lever, one link having a slidable pivotal connection with one of said devices, and the other 70 link having a similar connection with the other of said devices, each link being slidably fulcrumed between the points of its pivotal connection with the lever and its respective vending device, said links serving successively to shift said vending devices in opposite directions upon a throw of said lever in either direction.

5. In a machine of the class described, a pair of upright magazines, each adapted to receive a stack of boxes and being formed at 90 the bottom thereof with an opening for the removal therethrough of the lowermost box of the stack, a vending device for each magazine, each device being movable forward and back through its respective magazine to 95 deliver boxes one after the other through the delivery opening therein, each device being formed with a guard flange for closing the delivery opening of its respective magazine in the retracted position of the device, a reversely movable actuating member common to both of said devices and means connecting said member with said devices for successively shifting the same reversely upon movement of said member in either direction.

In testimony whereof, I have signed my name to this specification.

MARTIN BOHLIG.
